FIG. II

Inventor

Henry S. Hallwood

By *Shigley & Harney* Attorneys

UNITED STATES PATENT OFFICE.

HENRY S. HALLWOOD, OF COLUMBUS, OHIO.

MORTISING-MACHINE.

1,225,625.

Specification of Letters Patent.

Patented May 8, 1917.

Application filed February 1, 1916. Serial No. 75,543.

To all whom it may concern:

Be it known that I, HENRY S. HALLWOOD, a citizen of the United States of America, residing at Columbus, in the county of 5 Franklin and State of Ohio, have invented certain new and useful Improvements in Mortising-Machines, of which the following is a specification.

This invention relates to improvements in 10 mortising machines of the hand power type, and the invention is designed to provide a portable device of this character which is particularly adapted for use by the ordinary mechanic in mortising slots for tenons and 15 door locks, or recesses for hinges, and the like, at a minimum expenditure of time and labor.

Most of the machines now in use, with 20 which I am familiar, are provided with a positive feed mechanism, which, from its very nature, precludes its adaptation with equal effectiveness to soft, hard, or knotty wood, and, in addition, the very small screw feed requires that a great number of cuts be 25 made in securing the proper depth. In this improvement the feeding device is of such flexibility as to adapt it for cutting a mortise in any kind of wood with less time and labor, as will be hereinafter more clearly pointed 30 out.

In the accompanying drawings I have 35 illustrated one complete example of the physical embodiment of my invention, constructed according to the best mode I have so far devised for the practical application of the principles of my invention.

Figure 1 is an end view.

Fig. 2 is a side elevation.

Fig. 3 is a top plan view.

Fig. 4 is a transverse sectional view of the 40 supporting frame, showing a portion of the slideable carriage.

Fig. 5 is a longitudinal sectional view of a 45 portion of the supporting frame and carriage, illustrating the bit in dotted lines.

Fig. 6 is a vertical sectional view of the slotted or grooved stem for holding the bit.

Fig. 7 is a view in elevation of the bit.

Fig. 8 is a transverse sectional view of 50 the bit.

Fig. 9 is a diagrammatic view illustrating the machine supported at the edge of an upright door in order to drill horizontally into the wood.

Fig. 10 illustrates the position of the machine when drilling vertically into the wood.

Fig. 11 illustrates one manner of drilling the holes before the parts are reamed or chiseled out.

In the preferred embodiment of my invention, as illustrated in the drawings, I employ the rectangular bed or frame 1 having an open center and formed with an integral perforated ear 2 at each corner and beneath or at the underside of the bed. There are 60 four of these perforated ears to receive the four clamp screws 3 by means of which the bed may be clamped over the edge of a door, as indicated in Figs. 9 and 10.

The screw clamps are arranged in pairs 70 on each side of the door, and provide means for rigidly and securely holding the bed to the door.

At its ends the bed is provided with a pair of upwardly projecting lugs 4, 4 carrying cylindrical bars 5, 5 on which the carriage 6, rectangular at its base and having its corner sleeves 10 engaging the bars 5, is slideable by means of the threaded rod 7 engaging the lug 8 on the bed and swiveled to the 80 carriage at 9. The top center of the carriage is fashioned with a bearing sleeve or head 11 for the spindle 12 which is formed with a groove 13 in its surface, and the working head of the spindle is provided with a socket 85 14 and tapered bearing 14^a to receive the threaded end 15 and shoulder 15^a of the bit 16 which is thus rigidly and securely held. The bit is provided with the usual cutting flanges at its lower end for drilling holes in 90 the line of its axis, and for the purpose of removing fins between these bored holes, the bit is also provided with teeth projecting at an angle from the axis of the bit or drill and 95 located on the periphery of the drill. By the presence of the latter cutting devices, the carriage and drill may be reciprocated together to ream out the fins between the bored holes.

The spindle 12 is adapted to revolve and move both vertically and horizontally, and it is revolved through the medium of the handle 17, gear 18, pinion 19, shaft 20, pinion 21, gear 22 on its shaft and the 105 bevel pinions 23 and 23' supported in the carriage 6. The bevel gear 23', it will be noted, is supported on the grooved spindle 12, between a pair of lugs 24, 24 integral with the supporting bracket 25, and by 110 this construction the spindle is revolved, and at the same time permitted to pass

through the bevel gear 23' which is splined to the grooved spindle for this purpose.

The feed of the bit is accomplished through the instrumentality of a link 26, 5 slidable in the bearing lug 26' of the head 11 and connected to the upper end of the spindle by means of the screw 27 which is passed through a large perforation in the bent end 28 of the link. The screw is 10 headed and fixed in the spindle so that it turns with the spindle in the perforated bent end of the link, which, of course, does not revolve. At its lower end a handle 29 is formed on the link which may be grasped 15 by the operator to feed the bit while, with the other hand, the operator turns the crank handle 17 to revolve the bit, and the train of gears is so arranged as to drive the bit at a high speed. A gage collar 30 may be 20 adjusted to any desired position on the spindle and retained there by set screw 31, to gage or limit the depth of the hole bored by the bit, and by means of the recess or notches 32 in the link, and the pivoted pawl 25 33 on the head 11, the spindle may be held against progressive feed. If desired, a spring as 34* may be attached between a part of the carriage and the handle of the link in order to secure a continuous feed for 30 certain kinds of work. When the bit is to be fed by hand, of course the pawl 33 is freed from the link and turned to the right or left, as indicated in dotted lines Fig. 1.

By means of a pivoted pawl 34 on the 35 carriage and a series of spaced perforations 35 on the side bar, or bars, of the bed, the carriage may be moved longitudinally on the bars 5, 5 and held in adjusted position. In such case, the screw bar 7 is dispensed 40 with and the carriage is moved by the hand grasping the handle 36 which projects from the side of the carriage, as indicated in the modified forms of the invention, Figs. 4 and 5. For reaming or slotting, the pawl 45 is held up out of operative position, and then the frame is free to slide when pressure is applied either from the screw 7 or handle 36.

A pair of oppositely disposed hinged 50 braces 37, 37 located below the base of the carriage and suspended therefrom are designed to support a guide block 38 through which the upper end of the bit projects, and by means of the two set screws or bolts 39 55 carried by the hinged braces the bit may be held rigidly against lateral motion during the operation of reaming. In vertical boring the braces would be of no advantage to the bit, but when the carriage and bit 60 are pushed horizontally (the carriage sliding on its bed) while the bit is in the wood and cutting, the braces strengthen the shank of the bit near the surfaces of the wood to take the strain off the shank. 65 When not in use, these braces may be turned

up on their hinged supports as indicated in dotted lines at the right in Fig. 5.

The operation of the machine will be apparent from the preceding description and the drawings. The bit, after being secured 70 in the spindle, is revolved through the manipulation of the handle 17 and its train of gears, and the carriage may be set to various positions for drilling successive holes through the medium of the screw bar 7, or, if the 75 screw bar is not present, then by means of the handle 36 and the pivoted pawl or dog 34, as described, and the feed is accomplished by pulling down on the handle 29 of the feed link 26, the spring pawl 33 of 80 course being disengaged from the link.

In Figs. 4 and 5 the carriage is moved by the hand grasping the handle 36, the two fingered pawl 34 being adapted for retaining the carriage in set position if moved to 85 the right or left, as in Fig. 5. With the pawl 34 in position, shown in Fig. 5, the bit is adapted to drill, successively, holes A. C. E, Fig. 11, while, if the pawl is swung over to the right in Fig. 5 and the other finger 90 made to engage the openings 35, the drill will be in position to bore the holes B and D. This manner of cutting is provided for, in connection with the equidistant holes 35 of the series, by the fact that the fingers 34' 95 and 34^a of the pawl are at relatively different distances from the pivot point. This form of the machine is particularly adapted for work when the machine is located as in Fig. 10 and the door is standing on edge 100 and unhung.

In Fig. 9 the machine is applied to the door while it is suspended on its hinges, when the screw feed is essential. The size and weight of the machine permits of its 105 being carried about from place to place, and by means of the clamps or clamp screws 3, the machine may be applied to the edge of a door, either before or after it is hung.

While the machine illustrated is adapted 110 for manual power, it will, of course, be understood that mechanical or electrical power may be used to operate the drilling machine, and of course the machine is adapted for use in other ways than merely for cutting 115 mortises for door locks. A wide variety of cutting tools or bits may be used in the machine, such as reamers, hollow augers, taper augers, expansion or combination bits and the like, but it is the purpose of the inventor to use the one tool shown for the purpose of both drilling the holes A, B, C, D, E, and then for reaming or cutting away the "fins" left between the adjoining bores to complete and finish the mortise, without the 120 necessity of changing augers.

What I claim is:—

1. The combination in a drilling machine with a supporting carriage and a revoluble, reciprocable drill holding spindle, of hinged 130

braces connected to the carriage having adjustable means for holding the drill in rigid position.

2. The combination with a supporting carriage and a revolute, reciprocal drill holding spindle, of a pair of braces hinged to the carriage, and oppositely disposed set screws in the braces for retaining the drill in inflexible operative position.

10 3. The combination with a fixed bed hav-

ing a lineal series of equidistant holes therein, of a reciprocal carriage supported on the bed, a pawl pivoted on the carriage and provided with fingers of different radii adapted to engage said holes, a drilling tool 15 supported in the carriage, and operating means therefor.

In testimony whereof I affix my signature.

HENRY S. HALLWOOD.
